US00D698930S

(12) **United States Design Patent**
Sun

(10) **Patent No.:** US D698,930 S
(45) **Date of Patent:** ** Feb. 4, 2014

(54) **NAIL DEFORMITY CORRECTION DEVICE**

(71) Applicants: **Dong Jun Sun**, Seongnam-si (KR); **GD Korea**, Seongnam-si (KR)

(72) Inventor: **Dong Jun Sun**, Seongnam-si (KR)

(73) Assignees: **Dong Jun Sun**, Seongnam-si, Gyeonggi-do (KR); **GD Korea**, Seongnam-si, Gyeonggi-do (KR)

(**) Term: **14 Years**

(21) Appl. No.: **29/439,715**

(22) Filed: **Dec. 14, 2012**

(30) **Foreign Application Priority Data**

Jun. 14, 2012 (KR) 30-2012-0029196

(51) LOC (10) Cl. **24-01**

(52) U.S. Cl.

USPC **D24/192**; D24/107

(58) **Field of Classification Search**

USPC D24/107, 192, 231; 128/893, 894;
602/31

See application file for complete search history.

(57) **CLAIM**

The ornamental design for a “nail deformity correction device,” as shown and described.

DESCRIPTION

FIG. 1 is a perspective view of nail deformity correction device showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a reference view thereof.

The broken line showing of a finger is for the purpose of illustrating environment and forms no part of the claimed design.
